CLAIM

(21) Appl. No.: **29/444,584**

The ornamental design for an intraspinous process spacer implant, as shown and described.

(22) Filed: **Jan. 31, 2013**

DESCRIPTION

(51) **LOC (10) Cl.** **24-02**

FIG. 1 is a front right lateral perspective view of the intraspinous process spacer implant comprising my new design; FIG. 2 is a front left lateral perspective view of the design of FIG. 1;

(52) **U.S. Cl.**

FIG. 3 is a front elevational view of the design of FIG. 1; FIG. 4 is a back elevational view of the design of FIG. 1;

USPC **D24/155**

FIG. 5 is a left side elevational view of the design of FIG. 1; FIG. 6 is a right side elevational view of the design of FIG. 1;

(58) **Field of Classification Search**

FIG. 7 is a top view of the design of FIG. 1; and, FIG. 8 is a bottom view of the design of FIG. 1.

USPC ..... D24/155, 133; 623/17.11, 17.15, 17.16, 623/17.12; 606/90, 86 A, 248, 249

See application file for complete search history.

The broken lines in the figures are directed to the environment and are for illustrative purposes only; the broken lines form no part of the claimed invention.
